UNITED STATES PATENT OFFICE.

FRANK L. DIETZ, OF SEATTLE, WASHINGTON, ASSIGNOR, BY MESNE ASSIGNMENTS, TO
ONE-HALF TO EDWIN H. LUKE, OF SEATTLE, WASHINGTON.

SPLIT SHINGLE AND METHOD OF MAKING SAME.

Application filed December 10, 1926. Serial No. 153,889.

My invention or discovery relates to the art of splitting shingles, as distinguished from shakes.

My invention has for its object the splitting, from a block of wood, of shingles which have the naturally split grain of the wood on both upper and lower surfaces, and which taper substantially uniformly from a thick butt to a thin tip.

10 My invention relates, therefore, both to the method and to the product itself.

The accompanying drawings illustrate a typical shingle formed in accordance with my method and illustrate also, diagrammatically, the method itself.

Figure 1 is a perspective view of a shingle split out in accordance with my invention;

15 Figure 2 is a side elevation thereof, and Figures 3 and 4 are sections on the respective lines 3-3 and 4-4 of Figure 2;

20 Figures 5 and 6 are, respectively, plan view and elevation, illustrating the first step of my method, and Figures 7 and 8 are like views of the second step.

25 In this specification the term "shake" will be used as meaning a board, split from a block of wood, with its ends and its cross section through out generally of the same thickness. Such shakes, as commonly made 30 in the woods, are generally 36 inches in length, but may run from 24 to 40 inches long. The term "shingle" as used herein, will apply to a piece which is wedge shaped in longitudinal section, that is, thicker at the butt than at the tip, and gradually tapering 35 in thickness from butt to tip.

Shingles have heretofore been made from shakes by shaving away one or both surfaces, generally one only, to produce a taper from

40 butt to tip. Hand-made shakes were commonly made by the pioneers for use on their cabins, and have proven serviceable for many years, and where they desired to add a finishing touch to their cabins or public buildings, 45 they not uncommonly used such shaved shingles, manufactured by hand-shaving such shakes. This method, however, wasted approximately half of the wood in the shake, and this wood, being first-class, vertical-

50 grained stock, now has considerable value. It has, therefore, been proposed to saw shingles diagonally, as in the Runkle Patent, No. 1,577,935, and thus to form two shingles of one shake. This effected greater economy of 55 materials, while leaving the naturally rough

upper surface for effect and to provide drainage channels, as explained in Runkle's specification, but still left a sawed lower surface which could not in practice be left uppermost in the roof, and it frequently resulted in the saw running out, not in the end of the shake, but rather short thereof, so that the tip of one shingle thus formed was left uneven. This was generally due to the uneven surface of the shakes from which the shingles were formed. The patent to King, No. 1,593,800, illustrates one attempt to overcome this disadvantage, but such shingles as King's still have a sawed surface which should not be exposed in the roof.

70 According to my discovery, the shingles are split directly from the block and are split tapering, so that no finishing action whatever is required, and so that all of the wood is used without waste, the tips being generally sufficiently thick and even. Thus an economy both of wood and of labor is effected.

According to my method, I take a block of suitable wood, such as western red cedar, or any other wood which splits fairly evenly, the block being represented generally at 1 in the drawings, and employ a splitting or wedging instrument, of which the common frow represented at 2 is an example. This I place across the upper end 3 of the block 1, spaced from one edge 4 by an amount equal to the thickness of butt desired in the shingle. It is understood, of course, that the frow is so placed as to cut vertical grain shingles, for the method will not operate satisfactorily if cutting with a slash grain, the chief objection being that the split cannot be properly controlled.

With the frow thus placed, as in Figures 5 and 6, it is struck and driven sharply into the block, commencing a split in advance of the frow, as indicated at 5 in Figure 6. After the frow has been pushed a short distance into the wood, it is twisted to widen 100 and extend the split 5, as is common in the use of such tools. This operation is repeated as often as may be required, generally two or three times, as indicated by the frow marks 16 (Figure 1). Upon the completion 105 of this operation the shingle separates from the block, and it will be found that the split 5, instead of running parallel to the side 6 of the block, has naturally tended to taper out toward the bottom 7 of the block, so that 110

it runs out in the end 7 closely adjacent the lower corner 8. This taper is generally the same throughout the length of the shingle thus split off, given a fairly straight-grained block to start with.

Now, if the same process be repeated, driving the frow into the same end 3 of the block, all subsequent pieces split off would be shakes, that is, they would not taper. However, I have discovered that if the block is reversed end for end, as seen in Figure 8, with the end 7 uppermost and the end 3 on the ground, the same process may be repeated with the result that tapered shingles, not shakes, are formed. The frow 2 is placed in position across the end 7 inward from the edge 8' by an amount equal to the thickness of butt desired in the shingle, is driven into the block, commencing the split 20 5', and is then forced through the block, in the same manner as before, whereupon the split 5' tapers out towards the edge 4'. It will be understood that the corners 4 and 8 of Figure 6 are now in the shingle which 25 was first split off, and that the corners 4' and 8' are the corresponding corners of the block which remains.

The same process is repeated, reversing the block end for end after splitting off each shingle, and each such shingle will split off with a substantially even taper and with two naturally rough split surfaces.

The method just described is a hand method, but it lends itself as readily to machine production. However, it is desired to emphasize that the action is a splitting one, one in which the fibers are torn or separated, commencing at an end and proceeding always in advance of the wedge-like frow or other splitting tool. It must be distinguished from any slicing or cutting method, whether cutting from the end or from the side of a block. The frow or its equivalent is purely a wedge, splitting and parting the fibers ahead of it, and its sharp edge is only used to enter the block, and to hold the frow in proper relation thereto when the entering blow is struck.

A method equivalent to the hand method 50 described would consist in advancing the block towards the path of a reciprocable frow or frows, whereby the individual shingles are split off from a side of the block, commencing each time from alternate ends.

Such a shingle is shown in Figures 1, 2, 55 3 and 4. It will be noted in Figure 1 that the edge 11 of the shingle at the tip is straight, showing that the frow has entered here, and the diagonally opposite edge is straight. By reference to Figures 2 and 4, it will be seen that at the tip the upper surface of the shingle is fairly smooth, but that its under surface is uneven. This under surface was the inner side, that is, the side next 60 to the block when this shingle was split off,

and was the lower end of the block at that time. The butt end, on the contrary, shows the upper edge 12 as uneven, and the lower edge 13 as straight and smooth, for here again the frow entered as it commenced the 70 splitting of this particular shingle. Each such shingle is vertical grained.

It is immaterial which side of such a shingle is placed uppermost, as both have the naturally split surface, thus offering natural 75 channels, unmarred by feathers, such as are present in sawed shingles, down which channels the water may drain. Thus, instead of a shingle surface which may be placed uppermost, such shingles provide two such surfaces, and if the edges 14 and 15 are uneven, as shown best in Figure 3, that side may be placed uppermost which best fits with the adjoining shingles.

What I claim as my invention is:

1. A shingle tapered from butt to tip, and having upper and lower surfaces naturally split.
2. A split shingle having a butt thicker than its tip, and both its faces presenting a naturally split, rough surface.
3. A split shingle having a butt thicker than its tip, its upper and lower faces being generally plane, except as they present a naturally split rough surface.
4. A split shingle tapering substantially uniformly from a thick butt to a thin tip, both its faces presenting a naturally split, rough surface, the grain of the wood in the shingle being on edge with the faces and extending lengthwise of the shingle.
5. A split shingle tapering substantially uniformly from butt to tip, and both faces presenting a generally rough, naturally split surface, the end of one face near the tip, and of the opposite face near the butt being substantially plane, and merging into the rough surface.
6. A split shingle tapering from butt to tip, both faces presenting a generally rough, naturally split surface, the junction of one face with the tip end, and of the other face with the butt end, being a straight edge, and the faces merging gradually from such edges into the naturally split surfaces.
7. The method of splitting shingles from a wooden block which consists in driving a wedge into an end of the block, and spaced from its edge by an amount equal to the butt thickness desired, forcing the wedge endwise through the block, then similarly driving and forcing the wedge through the block at the same side, but from the opposite end.
8. The method of forming shingles from a block of wood which consists in splitting 125 individual shingles alternately from opposite ends of the block.
9. The method of forming naturally tapered shingles from a block of wood which consists in entering a wedge adjacent a side 130

of the block and forcing it through to split off an individual shingle, and then repeating the same steps each time from the opposite end of the block, until the block is 5 consumed.

10. The method of forming naturally tapered shingles from a block of wood which consists in entering a wedge lengthwise the grain, but transversely thereof, to form a 10 vertical grain shingle, and forcing the wedge through the block to split off an individual shingle, and continuing these steps but entering the wedge each time from the opposite end of the block.

11. The method of forming shingles from 15 a block of wood which consists in splitting an individual shingle from a side of the block, commencing at one end, then reversing the block end for end, and splitting a second individual shingle from the same 20 side, but commencing at the opposite end, then reversing the block and continuing as before, splitting always from the same side but commencing each time from the opposite end.

Signed at Seattle, King County, Washington, this 24th day of November, 1926.

FRANK L. DIETZ.
